[57] ABSTRACT

A ski boot toe fixture comprises a base adapted to be fixed on the upper surface of a ski, a turnable member holding a ski boot toe, a press connecting means connecting the base and the turnable member by resilient pressure, a boot toe holding top covering member and a second press connecting member connecting the boot toe holding member and the turnable member. The turnable member is arranged on the base to turn relative to the base around a vertical pin. The ratio of the space between the vertical pin and the second press connecting means to the space between the boot toe and the vertical pin is adjustable by an adjusting means.

FIG. 1

FIG. 2

SKI BOOT TOE FIXTURE

This application is a divisional of application Ser. No. 93232, filed Nov. 25, 1970, entitled "Ski Boot Toe Fixture," now U.S. Pat. No. 3,733,085.

The present invention relates to a metal fitting for a ski and more particularly relates to a ski boot toe fixture.

A ski boot toe fixture is usually fixed to the upper surface of a ski in order to settle a ski boot on the ski in cooperation with a ski boot heel binding which is also fixed to the ski. In a conventionally known ski boot toe fixture, there is provided a base plate to be fixed to a ski and a turnable member for holding the boot toe which is turnably provided on the base plate. A press connecting means, including, for example, a steel ball and the turnable member. According to this known structure, the turnable member turns laterally for disengagement from the ski boot toe to protect a skier from accidents such as a sprain, when unreasonable force, stronger than the predetermined strength, is applied to the boot toe. The strength of the force by which the said disengagement is performed varies according to the skill of skiers. Usually a screw for adjusting the spring force of the press connecting means is provided. In this device, however, adjustment of the spring force is terribly difficult for children and women since that force becomes larger as the screw is tightened more and more. On the other hand, it will cause inconvenience to purposely carry a means for screwing the screw. This device has another disadvantage that it is difficult to adjust the spring force accurately since the adjusting length is relatively short.

It is the objective of the present invention to provide a ski boot toe fixture which is easy to adjust and is adjustable accurately over a wide range.

According to the present invention, the ratio of the space between the boot toe received by a toe holding member and a connecting pin (fulcrum) to the space between the line of action of the spring force and said turnable pin, i.e., leverage, is adjusted instead of adjusting the spring force. By this construction, adjustment of the force by which the boot toe is released can be adjusted easily in a wide range.

As for the disengagement of the boot toe, it is advantageous for a boot toe holding means to be turned in a small radius of turning, as the boot toe may be thrust obliquely forward in that case. On the other hand, the small radius of turning of the toe holding means may cause difficulties in obtaining accurate adjustments of the force, by which the boot toe is released, by varying the leverage. The present invention solves this paradox by providing another connecting pin arranged near the end portion of the turnable member to constitute the axis of turning of the toe holding means, which second connecting pin is apart from the connecting pin constituting fulcrum of leverage. Thus the radius of the toe holding means becomes small, while the adjustment length is kept sufficiently long.

A fuller understanding of the present invention and its objectives and features may be had from the following detailed description of preferred embodiments with reference to the accompanying drawings, in which the similar parts are represented by the same reference numerals.

In the drawings:

FIG. 1 is a perspective exploded view of the preferred embodiment of the present invention prior to its assembly; and

FIG. 2 is a vertical sectional side view of the same after its assembly.

In the embodiment shown in FIGS. 1 and 2, the ski boot toe fixture comprises basically a base plate 10, a turnable member 20, a top covering member 60 for holding the boot toe, a press connecting means 30, a first connecting pin 40, and a second connecting pin 64.

The base 10 is provided with a pair of through holes 11. The base 10 is adapted to be fixed on the upper surface of the ski by means of wood screws (not shown) which penetrates through the holes 11.

The turnable member 20 comprises a casing enclosing a hollow space 28.

The first press connecting means 30 comprises a steel ball 31 and a spring 32 for pressing the ball 31, which are housed within the cylindrical housing member 34, as shown best in FIG. 2.

The connecting pin 40, is settled immovable and the press connecting means 30 is movable relative to the connecting pin. For this purpose, the bottom end portion of the pin 40 is secured and fixed to the bottom surface of the base 10 after it is penetrated through a hole 15 of the base 10. The turnable member 20 is provided with a bearing hole permitting the pin 40 to penetrate through, whereby the turnable member 20 is turnable around the fixed pin 40, on the base 10. The independent cylindrical member 34 enclosing the steel ball 31, spring 32 constituting the second press connecting means 30 is arranged within the hollow interior 28 of the turnable member 20. In order to move the press connecting means 30 lengthwise in the hollow interior of the turnable member 20, a feed screw 50 having an enlarged head 51 is inserted successively through a front end hole 24 of the turnable member 20, a pair of holes 36 of the cylindrical member 34 and a second hole of the turnable member 20. The feed screw 50 has an engaging ring at its end which is fitted on the screw shown in FIG. 2 so that the screw 50 may not slip out.

The space between the boot toe and the connecting pin 40 and the pressing force of the steel ball 31, delivered from the spring 32, are respectively fixed. Therefore, as the space between the pin 40 and the steel ball 31 becomes larger by moving the cylindrical member 34 away from the pin 40, by means of the feed screw 50 having the enlarged head 51, a larger force is required to disengage the ski boot toe, so that the boot toe becomes hard to be disengaged in proportion to said space.

In the preferred embodiment shown in FIGS. 1 and 2, the connecting pin 40 attached to the base plate 10 is turnably engaged in a through hole 29 of the turnable member 20. A top covering member 60, having a toe holding means 62, is pivotally attached on the turnable member 20 and turnably fixed thereto by means of a second connecting pin 64, which is arranged adjacent the rear end of the turnable member 20.

A steel ball 31 of the second press connecting means, which is movable within a hole 28 of the turnable member 20, is fitted in an elongated depression 63 (groove) provided on the bottom surface of the fore portion 61 of the top covering 60 to properly connect the turnable member 20 and the top covering 60. The connecting

pin 40 is provided with a blind hole 47 adjacent its rear bottom portion. A spring 48 and a steel ball 49, constituting a first press connecting means, are inserted in the hole 47, and the steel ball 49 is fitted in a depression 70 of the turnable member 20 to hold the same just parallel to the base.

In this embodiment the steel ball is pressed by the spring 32 contained in the cylindrical member 34. The cylindrical member 34 is moved forward or rearward by turning the feed screw 50 through the medium of the enlarged head 51, thereby freely varying the space between the connecting pin 40 and the steel ball 31, to thereby adjust the force by which the boot toe is released.

In this preferred embodiment, the engagements between the turnable member 20 and the top covering 60 and between the base plate 10 and the turnable member 20, by means of the respective steel balls 31 and 49, are broken when unreasonable force stronger than the predetermined strength is applied to the boot toe. At this time, the turnable member 20 is turned rightwardly or leftwardly around the connecting pin 40 and the top covering 60 is turned around the second connecting pin 64. Therefore, the boot toe holding means 62 is turned around the second pin which is arranged near the rear end of the turnable member 20, and the radius of turning will be small. The boot toe is thrust forwardly obliquely relative to the base 10 at the time of disengagement.

The cylindrical member 34 has a protrusion 38 showing the position of the cylindrical member 34 through a window 71 of the turnable member 20.

Modifications may be made in the present invention within the scope of the subjoined claims.

We claim:

1. A ski boot toe fixture comprising a base adapted to be fixed on the upper surface of a ski and having a vertical pin, a turnable member for holding a boot toe, said turnable member being arranged on said base and turnable around said vertical pin relative to the base, said turnable member comprising a casing having an interior space, said interior space being longitudinally elongated and extending generally vertically, a first connecting means interposed between said base and said turnable member to connect the base and the turnable member by means of resilient pressure, a top covering member having a boot toe holding means comprising two outwardly extending arms which extend from the rear portion thereof, said top member having a forwardly extending upper portion, said top covering member having a longitudinally extending depression formed in the inner surface of said forwardly extending upper portion, means to turnably mount said top covering member to said casing, a second connecting means comprising a housing member, a spring and a pusher, with said spring and at least part of said pusher being within said housing member, said second connection means being positioned in said elongated space of said casing of the turnable member, said pusher normally being forced into said depression of said top covering, and adjusting means consisting of a feed screw which can effect longitudinal displacement of said housing member within said interior space of said casing of the turnable member.

2. A ski boot toe fixture as claimed in claim 1 wherein said first connecting means comprises a spring and a pusher inserted in a hole provided in the rear portion of said vertical pin, said pusher normally being forced in a depression of the turnable member.
